UNITED STATES PATENT OFFICE.

FRANCIS JOSEPH LEISEN, OF METUCHEN, NEW JERSEY, AND EDWIN S. DUNN, OF HUNTINGTON, WEST VIRGINIA.

TUNNEL-KILN.

1,345,605.

Specification of Letters Patent.

Patented July 6, 1920.

Application filed January 31, 1919. Serial No. 274,319.

To all whom it may concern:

Be it known that we, FRANCIS JOSEPH LEISEN and EDWIN S. DUNN, citizens of the United States, and residents of Metuchen, in the county of Middlesex and State of New Jersey, and Huntington, in the county of Cabell and State of West Virginia, respectively, have made certain new and useful Improvements in Tunnel-Kilns, of which the following is a specification.

Our invention relates generally to kilns, and more particularly to that type of kiln known as a tunnel kiln, wherein the articles to be burnt, irrespective of their particular nature, are mounted or supported upon movable carriers, these carriers being intermittently advanced through the kiln at regular periods, and in a continuous line, so that each carrier with its load enters one end of the tunnel of the kiln with dried material thereon, and emerges from the opposite end of the tunnel with the burnt articles, having been subjected to various degrees of drying and burning heat, and then to cooling drafts, so that upon emerging from the kiln, the articles are burnt and have been cooled to an extent permitting of their rehandling in order to avoid the necessity for the great storage spaces kilns of this character now require.

Our invention is directed in particular to a novel arrangement of the parts of the kiln, so as to bring about greatly increased effectiveness in the speed of operation, as well as a greatly increased efficiency, and proposes not only a rearrangement as regards the ordinarily constructed kiln of this type, but certain new features of a nature calculated to efficiently coöperate with the rearranged form.

In the accompanying drawing forming our present improvements:—

Figure 1 is a side elevation of our improved kiln complete;

Fig. 2 is a horizontal section taken lengthwise through the kiln structure, and of a more or less diagrammatic nature, having the various attachments removed;

Fig. 3 is a transverse vertical section taken substantially on line 3—3 of Fig. 1;

Fig. 4 is a similar view taken substantially on line 4—4 of Fig. 1;

Fig. 5 is another similar view taken substantially on line 5—5 of Fig. 1;

Fig. 6 is another similar view taken substantially on line 6—6 of Fig. 1;

Fig. 7 is a front elevation of one of the fire zones, and,

Fig. 8 is a section through one of the fire zones taken parallel to its front wall.

Referring now to these figures, our invention relates to that type of kiln which embodies an elongated tunnel generally indicated at 10, the entrance end 11 and the exit end 12 being in practice normally closed by somewhat similar doors, opening of which respectively permits of the introduction and removal of material. Cool air is admitted to the exit end of the tunnel through ventilating doors 12^a, as will be more fully described hereinafter.

In the present instance, the kiln tunnel 10 has a covering arch 13 between the upper portions of its side walls 14, as best seen in Fig. 5, these side walls 14 being built upwardly upon what is preferably a solid masonry foundation 15, at opposite sides of a trough in the foundation through which rails 16 are led.

In the formation of the foundation, its upper surface, longitudinally alongside the walls 14, is formed with grooves 15 into which the lower ends of the buck-staves 17 are disposed at any desired points, and by virtue of which grooves the buck staves may be variously spaced more or less in accordance with the thickness of the walls 14. The upper ends of these buck staves are connected as usual by rods 18, and turn buckles 19, and the inner surfaces of the walls 14 above the foundation 15 are formed with longitudinal side grooves 20, into which the side edges of the platform 21 of the article supports in the nature of trucks extend, these trucks having wheels 22, which roll upon the tracks 16, and movement of which from the entrance end 11 of the kiln tunnel to its exit end 12 is facilitated by virtue of a slight declination of the entire tunnel from end to end, as indicated in Fig. 1, the degree of which is just sufficient to provide for easy movement of the cars without the danger of their unassisted movement.

Intermediate the ends of the tunnel 10 of the kiln, the space within the same communicates with successive fire zones 23, 24 and 25, and into each of these zones the

side walls 14 of the kiln tunnel have openings 26, as seen particularly in Fig. 4, which openings, it will be noted, are above the level of the grooves 20 of the side walls, 5 so that the heat thrown into the tunnel from each fire zone will emerge therein at a point above the cars supporting the articles to be fired.

The lower portions of the side walls 14 10 within each of the fire zones are thickened as seen in Fig. 4 to form baffle walls 27, against which the heat is deflected upwardly into the openings 26 and thus given a tendency to upward movement immediately upon 15 its passage through the openings 26 and into the interior of the tunnel. In this way and through the movement of the side edges of the car platforms 21 within the grooves 20, the lower portions of the cars, that is, the 20 trucks and wheels, are protected from the intense heat, and with front and rear ends of cars in abutting relation entirely throughout the length of the kiln tunnel, it is obvious that the space below the car platforms 25 may be made a cooling channel from end to end of the kiln.

It is also obvious from the foregoing description that in operation, each car with its dried products for burning, is thrown into 30 the influence successively of the fire zones 23, 24 and 25, the zone 23 being for instance 1500 degrees Fahrenheit, the zone 24, 2000 degrees Fahrenheit, and the zone 25, 2500 degrees Fahrenheit, thus increasing the heat 35 in the direction of progressive movement of the cars through the kiln, which is brought about not only by the increase of heat at the fire zones, but which is permitted by virtue of the disposition of the stack 28 at a point 40 between the fire zone 25 and the exit end 12 on the tunnel, so that the zone 25 is nearest the stack and the latter draws the products of combustion and the heat from each 45 of the fire zones in the direction of movement of the cars through the kiln.

The stack 28 as seen in Fig. 3, has its opening controlled by a damper 29, and is arranged at one side of the tunnel 10 with its opening in communication therewith 50 through an opening 30, and is disposed at the relatively opposite side of the tunnel with respect to a chamber 31 built at one side of the tunnel, and in communication with the tunnel opening through an opening 32, this 55 chamber 31 having an upwardly extending pipe 33 leading therefrom and communicating with the stack opening through an opening 34 controlled by a damper 35. This pipe 33 also communicates with a pipe 36 extending 60 forwardly above the kiln and communicating at its forward end with a fan casing 37, the fan within which sucks through the pipe 36 and discharges into a pipe 38, projecting forwardly from the fan 65 casing 37 and in turn communicating with

branch pipes 39, which enter opposite sides of the kiln, through its side walls 14 as seen particularly in Fig. 6, these branch pipes 39 being let into the kiln at a suitable point between its entrance end 11 and the first fire 70 zone 23 of lowest heat.

Thus in operation, the cars with their dry products are pushed into the entrance 11 of the kiln and proceed under moderate heat which gradually raises their temperature 75 until they reach a point opposite the branch pipes 39 when they are subjected to the lowest degree of heat of the kiln. The material is then subject to this same heat until it arrives at the first fire zone 23, and bearing in mind that the cars are moved intermittently at regular intervals, and that each car remains stationary during an interval between movements, at each of the fire zones 23, 24 and 25, it is obvious that each of these 80 fire zones is in length equal to the length of a car. From this fact it is further obvious that the spaces between the fire zones will be equal to the lengths of two cars, as shown in Fig. 2, so that each car will be subjected 85 first to the heat of the fire zone 23 until during successive movements it arrives opposite the fire zone 24, and that it will then be subjected to the heat of the fire zone 24 until during successive movements it arrives 90 opposite the fire zone 25. It is furthermore obvious that it will be subjected to the heat of the fire zone 25 until after it has passed the stack 28, and that up to the time it arrives opposite the stack it has been continuously subjected to increasing degrees of heat flowing through the tunnel of the kiln in the direction of its travel through the kiln.

The stack 28 disposed between the series of fire zones and the exit end of the kilns 105 obviously brings the foregoing about, and likewise draws cooling air from the exit end 12 of the kiln through the ventilating doors 12^a, so that as each car passes the stack 28 it is at once subjected to this cooling draft 110 which becomes of course cooler as the car approaches the exit end 12. The cool air which enters the tunnel through the ventilating doors 12^a is of course heated during its passage to the stack where it may be conducted to a drying kiln for utilizing this 115 heat, which is ordinarily wasted, to effect a drying of the ware before it is introduced to the tunnel kiln.

Through the kiln constructed as above, we 120 obtain maximum efficiency from the heat utilized in the operation and much greater efficiency through the relative arrangement of the parts as proposed than it is possible to accomplish with the usual tunnel kiln 125 where the heat products flow in a direction opposite to that of the movement of the products through the tunnel.

Our improved arrangement enables us to readily cut out one of the fire zones if 130

found expedient in connection with the burning of certain classes of ware, and permits of a much speedier operation and reduction in the time intervals between movements of the ware in the kiln and consequently a very material reduction in the time of the passage of ware completely through the kiln.

As shown in Fig. 3, the stack 28 may communicate at its lower end by a side opening 40 with a boiler 41 in turn communicating with the upper portion of the stack through a pipe 42 having a damper 45 and in this and in other ways, certain of which we will now mention, we may take advantage of the ordinarily wasted heat products, and turn the same to useful purposes.

For instance, steam pipes 44 may be extended longitudinally through the upper portions of the tunnel walls 14 at the sides of the arch 13, these points being the points of greatest heat, so that the steam generated in these pipes may be transported for use at other points, and in connection with various apparatus.

The several fire zones 23, 24 and 25 may utilize various fuels for instance coal, oil and gas, and if gas is utilized, particularly natural gas, the pipes 44 may be utilized to preheat the gas, as preheated gas is capable of much more economical use than if unheated. In the pipes 44 the gas may be preheated to a very high degree, there being no danger of combustion until the gas is mixed with air at the burners, one of which is seen at 45 in Fig. 7 and to which the gas is led from the pipes 44 through branch pipes 46.

In connection with either fuel it will be noted that the outer fire openings 47 of the fire zones are located at the lower portions of the outer walls 48 of these fire zones and upon horizontal planes below the plane of the openings 26 of the tunnel walls through which the heat products find their way into the interior of the tunnel so that the heat, as before stated, strikes the bridge walls 27, and is thereby given a greater tendency toward upward movement than would otherwise be present.

When it is desired to utilize a portion of the heat within the kiln for heating the water within the boiler 41, the dampers 35 and 45 are opened and the damper 29 closed thereby causing the heat from the kiln to traverse the pipe 33, the opening 34 and downwardly within the stack 28 and beneath the boiler 41 through the opening 40. The heat passes around the boiler 41 and upwardly into the stack 28 through the pipe 42.

We claim:

1. A kiln of the character described having a tunnel through which material to be burnt is intermittently moved from end to end, a series of fire zones spaced apart

in the length of the kiln and communicating at separate points with the tunnel thereof, and intermediate the ends of the latter, and a stack communicating with the tunnel at a point between the series of fire zones and 70 the exit end of the tunnel whereby to draw the heat products from the fire zones in the direction of movement of material through the tunnel from its entrance to its exit.

2. A kiln having a tunnel provided with 75 an entrance at one end and an exit at its opposite end, fire zones communicating with the tunnel at separate points in the length of the kiln, and a stack in connection with the tunnel between the several fire zones and 80 the exit end of the tunnel, as described.

3. A kiln having a tunnel provided with an entrance at one end and an exit at its opposite end, fire zones communicating with the tunnel intermediate the ends of the kiln, 85 a stack in communication with the tunnel at one side of the several fire zones, and means for withdrawing products from the stack and introducing the same into the tunnel at the relatively opposite side of the several 90 fire zones.

4. A kiln having a tunnel provided with an entrance at one end and an exit at its opposite end, fire zones communicating with the tunnel at separate points in the length 95 of the kiln, a stack in connection with the tunnel between the several fire zones and the exit end of the tunnel, and means for withdrawing products from the stack and introducing the same into the tunnel at a 100 point between the fire zones and the entrance end of the tunnel.

5. A kiln having a tunnel provided with an entrance at one end and an exit at its opposite end, a series of fire zones spaced apart 105 lengthwise of the kiln and separately communicating with the tunnel, a stack in communication with the tunnel between the exit end thereof and the several fire zones, and means for withdrawing heat products 110 from the tunnel adjacent to the stack and introducing the same into the tunnel between the entrance end thereof and the several fire zones.

6. A kiln having a tunnel provided with 115 an entrance at one end and an exit at its opposite end, a series of fire zones spaced apart lengthwise of the kiln and separately communicating with the tunnel, a stack in communication with the tunnel between the 120 exit end thereof and the several fire zones, means for withdrawing heat products from the tunnel adjacent to the stack and introducing the same into the tunnel between the entrance end thereof and the several fire 125 zones, and the said last named means having connection with the stack to withdraw products from the latter.

7. A kiln having a tunnel provided with an entrance at one end and an exit at its 130

opposite end, a series of fire zones separately communicating with the tunnel at points intermediate the said ends, a stack in communication with the tunnel at a point between the several fire zones and the exit end of the tunnel, an air chamber in communication with the tunnel adjacent the stack, a pipe leading along the kiln from the said air chamber, a second pipe having branches let into the tunnel at points between the entrance end of the tunnel and the said fire zones, and a fan for creating suction through the first named pipe and arranged to deliver into the second pipe for the purpose described.

8. A kiln having a tunnel provided with an entrance at one end and an exit at its opposite end, a series of fire zones separately communicating with the tunnel at points intermediate the said ends, a stack in communication with the tunnel at a point between the several fire zones and the exit end of the tunnel, an air chamber in communication with the tunnel adjacent the stack, a pipe leading along the kiln from the said air chamber, a second pipe having branches let into the tunnel at points between the entrance end of the tunnel and the said fire zones, a fan for creating suction through the first named pipe and arranged to deliver into the second pipe, said first named pipe having connection with the stack, as described.

9. A kiln having a tunnel provided with an entrance at one end and an exit at the other, fire zones communicating with the tunnel, and means for creating a draft in the tunnel so that the products of the fire zones move in the direction of the exit end of the tunnel.

10. A kiln having a tunnel provided with an entrance at one end and an exit at the other, fire zones communicating with the tunnel, a pipe in circuit communication with the tunnel at points in the front and rear of the fire zones, and means for creating a draft in the pipe and tunnel so that the products of the fire zones move through the tunnel in the direction of the exit end thereof.

11. A kiln having a tunnel provided with

an entrance at one end and an exit at the other, fire zones communicating with the tunnel and of progressively increasing intensities from the entrance end to the exit end, and means for creating a draft through the tunnel so that the products of the fire zones move in the direction of the exit end of the tunnel.

12. A kiln comprising a tunnel through which material to be burned is adapted to be moved in one direction, means for generating heat within the tunnel, and means for forcing the heat in the same direction as the material is moved.

13. A kiln comprising a tunnel through which material to be burned is adapted to be moved in one direction, means for generating heat within the tunnel, and means for forcing the heat in the same direction as the material is moved for a portion of the length of the tunnel and returning part of the products of combustion to a point in advance of the heat generating means.

14. A kiln comprising a tunnel through which material to be burned is adapted to be moved in one direction, means for generating heat within the tunnel of intensities progressively increasing in the direction in which the material is moving, and means for forcing the heat in the same direction as the material is moved.

15. A kiln comprising a tunnel through which material to be burned is adapted to be moved in one direction, means for generating heat within the tunnel of intensities progressively increasing in the direction in which the material is moved, and means for forcing the heat in the same direction as the material is moved for a portion of the length of the tunnel and returning part of the products of combustion to a point in advance of the heat generating means.
